(Cl. D9—2)

It is to be understood that the broken lines representing the bristles cover the entire area indicated by the dot-dash lines.

The dominant features of my design reside in the portions shown in full lines.

I claim:

The ornamental design for a hair brush, as shown and described.
